Attorney

UNITED STATES PATENT OFFICE.

WILLIAM A. ZEIDLER, OF NEW YORK, N. Y.

IRONING MACHINE.

Application filed December 13, 1920. Serial No. 430,312.

To all whom it may concern:

Be it known that I, WILLIAM A. ZEIDLER, a citizen of the United States, residing at New York, in the county of Bronx and 5 State of New York, have invented certain new and useful Improvements in Ironing Machines, of which the following is a specification.

This invention relates to improvements in 10 ironing machines and the like, and has for its primary object to provide a simple and effective means for applying pressure to the feed rolls during the ironing operation, and quickly releasing and raising them 15 from the work, the same means being adapted to lock said rolls in position during the operation.

Another object of the invention is to provide improved means for interconnecting 20 said rolls, providing an independent and co-operative action insuring equalization of applied pressure between them. A further object of the invention is to provide an improved hot-plate having a plurality of 25 channels upon the ironing surface, each with a declining entry in order to insure positive feeding action to the rolls. A further object of the improved hot-plate is to provide means to apply a current of heated 30 air from the interior of the plate to the work after being ironed in order to assist in the drying.

With these and other objects in view, the invention resides in the combination and 35 arrangements of parts as will be hereinafter more fully set forth in the accompanying specification and drawings, in which—

Figure 1 represents an end elevation of my improved ironing machine;

40 Figure 2 represents an enlarged cross-sectional view of the hot-plate of the machine with the rolls partly broken away, shown in the ironing position;

45 Figure 3 represents an enlarged side elevation of the member 22, with a tension rod and spring in place;

50 Figure 4 represents a top plan view of the machine with the rolls and hot-plate broken away in order to show the operating pedals, etc.

Figure 5 represents an enlarged rear elevation of the hot-plate.

Figure 6 represents an enlarged sectional view of a modification of the hot-plate, with the rolls, in the ironing position 55 and the frame of the machine indicated by dotted lines.

In the embodiment of my invention herein illustrated, 1—1 represent standards or legs, arranged two at each end of the machine, connected by suitable cross braces 1^a at the top and carrying the upwardly facing heated member 2 and the feeding board 3 approximately level with the working surface thereof. This table is formed preferably of hard wood, provided with an overhanging lip 3^a of metal, approaching but not touching the heated member 2. This heated member is made of metal and is shown as formed with two longitudinal 70 channels, 2^a—2^b, upon its surface so formed that the bottom of each channel is reached from the top by a gradual incline as shown.

The rear wall of the heated member 2 is here provided with a series of perforations, 2^c, the purpose of which will be shown later, and while this member may be heated in any approved manner, it is shown in this instance provided with a gas burner 4, connecting with a gas conduit 5. Beneath 80 the burner 5 is a casing 6 formed of porous material which extends around and about the lower and side parts of the hot-plate 2 in order to prevent contact therewith, either by an article 1 being ironed or 85 the operator.

Pivots mounted upon brackets 7—7 located, one upon each end of the top of the machine at the side of the heated member opposite the feeding board, are jointed arms, 90 each of which comprises two links, 8 and 9, respectively. Two cloth covered rolls, 10 and 11, respectively, are journaled between these arms, the centrally disposed shaft 10^a of the roller 10 pivotally connecting the ends 95 of the links 8 and 9, while the roller 11 is journaled between the free ends of the links 9—9 at either side of the machine.

Rotatably mounted upon a stud 7^a, of the bracket 7 at the left side of the machine, is a 100

worm gear 12 meshing with a worm 13, mounted upon a shaft 14, which is journaled within the member 15 as shown. A grooved pulley 16 is mounted upon the outer end of the shaft 14, and is connected by a belt 17 to the pulley 18^a of an electric motor 18. A sprocket wheel 19 is centrally mounted upon the face of the worm gear 12, and is connected by a sprocket chain 20 to a larger sprocket wheel 21 mounted upon the left end of the shaft 11^a of the roller 11. Upon the right ends of the shafts 10^a and 11^a of the rollers 10 and 11 are mounted sprocket wheels 22 and 23, respectively, which are connected by a sprocket chain 24 as shown. It follows that the motor driving the pulley 16 will impart motion to the roller 11 through the sprocket chain 20, and thence to the roller 10 through the sprocket chain 24 connecting the sprocket wheels 22 and 23.

It will be seen that the compound arms carrying the rolls 10 and 11 may be flexed due to the pivotally connected links 8 and 9, and in order to limit this movement, each link 8 is formed with a squared projection 8^a at the head, while the links 9 are formed with a lug or stop 9^a upon the inner side as shown in Figure 4. The projection 8^a and the lug 9^a are in close proximity, so that the flexing movement of the links 8 and 9 is limited by the distance between the projection 8^a and the lug 9^a.

A longitudinal shaft 25, journaled within the cross braces 1^a—1^a at each side of the machine, carries permanently affixed crank arms 26—26, one at each end, and each of these crank-arms is provided with a pivotally mounted member 26^a, through which a rod 27 freely passes. The rods 27 are pivotally connected at their upper ends with the links 9—9, at a point midway between the rolls 10 and 11, and their lower ends, beyond the member 26^a, are each provided with a nut 27^a, set with a jam-nut 27^b. A coiled spring 28 is disposed upon the rod 27 between the nut 27^a and the member 26^a, and another nut 27^c is located upon the rod 27, above the member 26^a. Therefore power applied to the rods 27 from the cranks 26 to raise the rolls 10 and 11 would be against the nuts 27^c, while power applied to the rods 27 to lower the rolls would be through the medium of the spring 28 against the nut 27^a. A lug 1^b formed integral with the cross-brace 1^a, at each end of the machine acts as a stop for the corresponding arm after it passes the down center when the rolls are in the ironing position. While in this position they are held depressed against the heated member with a force depending upon the tension of the spring 28, which in turn depends upon the adjustment of the nuts 27^a and 27^c.

Two arms 29 and 30, respectively, are also permanently mounted upon the shaft 25 at

a point intermediate its ends and extending in opposite directions. The arm 29 is connected with a pedal lever 31 by a rod 32, and the arm 30 is connected with another pedal lever 33 by a rod 34. The pedal lever 33 is provided, close to its front end, with a pivoted latch member 35 having teeth 35^a adapted to engage a longitudinal brace 1^d at the front of the machine. The latch member 35 is held in contact with the brace 1^d by a coiled spring 36, as shown. A shelf 37 is disposed between the standards 1—1, at a point below the hot-plate 2 in order to receive articles from the ironing rolls, and the shelf 37 is provided with a hinged extension 37^a. An electric switch 38 is mounted upon one of the standards 1, and is provided with an actuating lever 38^a adapted to engage a member 39 mounted upon and affixed to one of the rods 27, so that when the rods 27 are moved upwardly to raise the rolls 10 and 11 from the ironing bed 2, the switch 37 will be opened, stopping the motor, but when the rolls are lowered to the ironing position as shown in the drawings, the switch 38 will be automatically closed and the motor will be started.

In the modification of the hot-plate or ironing bed illustrated in Figure 6, it will be noticed that the contours of the channels formed on the ironing surface differ from those shown in Figure 2. In Figure 6 the channels 40^a—40^b of the hot-plate 40 are curved downwardly from the front of the plate, forming arcs of greater radii than that of the rolls, while the back of the first channel 40^a conforms to the roll 11, curving upwardly to the surface of the plate 40, and the back of the second channel 40^b curves downwardly at the rear edge 1^a as shown. In this manner, a wide, gradually lessening curved throat is formed at the front of the rolls in order to facilitate the feed, the upwardly inclined rear portion of the first channel 40^a acting to flatten out any fullness of the goods created during the passage of the goods through the first channel. The abrupt downward curve 40^b permits the goods to assume a natural curve over the hot-plate 40 downwardly to the receiving shelf. This entirely eliminates any wrinkling or fullness that may be caused in folded articles passing through the channels 40^a—40^b. The rear walls are provided with a series of perforations 40^c, similar to those shown in the hot-plate 2, as shown in Figures 1 and 5.

In operation the article to be ironed is spread upon the shelf 3 and introduced into the first channel 2^a of the hot-plate 2. The rolls 10 and 11 are then lowered to the ironing position by releasing the pedal 33, the switch 38 being closed by the downward movement of the rod 27. This brings the arm 26 only part way down but leaves the

rolls 10 and 11 resting on the heated member or ironing board solely by their own weight and with all other associated parts the two rolls being free to rise and fall relatively to each other throughout a small distance permitted by the stops 8^a, 9^a. The articles are rapidly smoothed and dried not only by this pressure but by being drawn over the rounded portion of the heated member or ironing bed which rises between the two rolls. This conformation of the bed combined with its wide extent produces a quick drying and since the evolution of steam is permitted by the small diameter of the rolls 15 and the considerable distance between them the machine operates very rapidly. In case a higher degree of pressure is desired than is produced merely by the weight of the rolls, the second pedal 31, is depressed to 20 the position shown in Fig. 1, which moves the arms 26 past their dead centers until they engage the stops 1^b. The rods 27 being attached to the mid-points by the links 9, the pressure of the rolls is equalized 25 while permitting them to yield against the springs 28.

The article after ironing passes backwardly over the hot-plate 2 and over its rear wall, the perforations 2^b of which permit the direct application of heated air from the burner 4 to assist in drying the article ironed, which falls to the shelf 37.

The rolls 10 and 11 are raised by foot pressure applied to the pedal 33 acting on the rod 34, the arm 30, shaft 25, arms 26, and rods 27 connecting with the links 9—9 of the articulated arms carrying the rolls. As the pedal 33 is depressed, raising the rolls, the teeth 35^a of the latch member 35 engage the brace 1^d, holding the rolls in the raised position, the switch 38 being opened by the upward movement of the rod 27. When it is desired to lower the rolls, a quick downward thrust upon the pedal 33 is sufficient to disengage the latch member 35, or the pedal may be depressed slightly and the latch member disengaged by the toe or other means. When either pedal is depressed the other is always elevated. Pedal 31 is locked 50 in depressed position by the movement of the arms 26 past dead center, but is unlocked and raised by depressing the pedal 33.

I claim:

1. In an ironing machine, a roll, a plurality of pedals, means inter-connecting said roll and pedals adapted for raising and lowering the roll upon a downward and upward movement of one of the pedals, and means connecting with the first means for increasing the pressure upon the roll upon a downward movement of another of said pedals.

2. In an ironing machine, an upwardly facing heated member, a pair of padded rolls located thereabove and cooperating therewith, a mounting for the rolls adapted for

flexing at the axis of one of the rolls, and means for depressing the rolls independently and for raising said rolls simultaneously.

3. In an ironing machine, an upwardly facing heated member, a pair of parallel padded rolls located above said heated member, a pair of arms pivoted at one side of said heated member and having one of said rolls journaled between the free end thereof, a second arm pivoted to each of said first arms upon an axis coincident with the roll axis, the second roll being journaled between the free ends of the last pair of arms, and operating devices attached to said last arms intermediate said rolls whereby said rolls are elevated and depressed. 70

4. In an ironing machine, an upwardly facing heated member, a pair of parallel padded rolls located above said heated member, a pair of arms pivoted at one side of said heated member and having one of said rolls journaled between the free ends thereof, a second arm pivoted to the free end of each of said first arms upon an axis coincident with said first roll, the other of said rolls being journaled between the free ends of said last pair of arms, means permitting limited angular movement of said second arms relatively to said first arms, and operating devices attached to said last arms intermediate said rolls whereby said rolls are elevated and depressed. 80

5. In an ironing machine, in combination, a heated member, a padded roll adjacent thereto, bearing members for said roll, a rock shaft parallel to said roll and having arms thereon, a pair of pedals operatively connected to said rock shaft, connections between said arms and said bearing members adapted to move said roll toward and away from said heated member upon operation of one of said pedals, the second of said pedals being arranged to effect a further rotation of said rock shaft to move said roll against said heated member with increased pressure. 100

6. In an ironing machine, in combination with an upwardly facing heated member, a roll located above said heated member, bearing members for said roll located at each end thereof, a rock shaft parallel to said roll below said heated member and having arms at its ends, an operating rod connecting each of said arms to the corresponding bearing member, each rod being of such length that the weight of said roll and associated parts will depress said arm to a point which is short of dead center, a pedal operatively connected to said rock shaft adapted to raise and lower said arms, and a second pedal connected to said rock shaft adapted to depress said arms past their dead center. 110

7. In an ironing machine, a heated member, a roll located above said heated member, a bearing member at each end of said roll, a rock shaft below said heated member 120

and having an arm at each end, a pivoted member carried by the end of each arm and having an aperture therethrough transverse to its pivot axis, an operating rod attached to each of said bearing members and passing loosely through the aperture in the corresponding pivoted member, fixed stops on each of said rods above and below the cor-

responding pivoted member, a spring interposed between each pivoted member and the stop which lies below the same, and means for rotating said rock shaft and for holding it at different positions of its rotation.

In testimony whereof I affix my signature.

WILLIAM A. ZEIDLER.
